UNITED STATES PATENT OFFICE.

EDWIN F. DAVIS, OF CENTRALIA, KANSAS.

MAIL-BAG.

SPECIFICATION forming part of Letters Patent No. 416,576, dated December 3, 1889.

Application filed April 22, 1889. Serial No. 308,091. (No model.)

To all whom it may concern:

Be it known that I, EDWIN F. DAVIS, of Centralia, Nemaha county, Kansas, have invented certain new and useful Improvements 5 in Mail-Bags, of which the following is a full, clear, and exact description, reference being had to the accompanying drawings, forming a part hereof.

This invention relates to that class of mail 10 bag or pouch fastenings wherein a series of locking devices are adapted to be locked or released in a single operation; and the nature of the invention consists of the novel combination of parts and their construction, as will 15 fully appear from the following description and accompanying illustrations, in which—

Figure 1 is a front elevation of a portion of a mail bag or pouch having my invention applied thereto. Fig. 2 is a sectional elevation 20 taken on the line $x-x$ of Fig. 1. Fig. 3 is a similar section taken on the line $y-y$ of Fig. 1, the cover-flap being extended or shown in its open position; and Fig. 4 is a detailed 25 perspective view of my invention shown in connection with a broken-away portion of the bag or pouch.

In the embodiment of my invention I employ a number of rocking crank-shafts C , which are supported in alignment with each 30 other in bearings or boxes d , riveted to one side of the bag A , near its upper end. These shafts are provided with cranks or loops C' , to which are strapped or clipped the bevel-ended drop-bolts D , which pass through and 35 are guided in their movements by guide-staples $b b$. These staples are themselves passed through plates or shields c , riveted to the bag A , the staples also being carried through the bag and riveted upon the inside 40 of the latter.

To the cover-flap A' is riveted or secured a series of locking-staples $a a$, projecting from the rear side thereof, and which when the flap is carried over the mouth of the bag or pouch 45 to close the same are passed through the usual apertures provided in the rear side of the bag or pouch thereof, and thence through apertures in the front side of the bag or pouch, and immediately or almost at the same 50 time through transverse openings in the plates or shields c . These staples $a a$ receive

and through them pass the bolts D , as shown, and thus secure the flap A' in its closed position over the mouth of the bag or pouch.

$g g$ are the locking-hasps, which are slightly 55 bent outward at their upper ends, and each has a swiveled or pivotal connection, by means of a right-angled or stepped link f , with a pintle-shaped terminal f' on the inner opposite end of each rocking crank-shaft 60 C . These hasps rest flat one upon the other, and are provided with coincident openings, through which is passed or received a staple h , riveted to the front of the bag, and to which is applied the shackle of a padlock i , 65 thus locking the various bolts in their staples and the bag or pouch flaps in place over the mouth of the latter. It will be seen that when the shackle of the padlock is withdrawn from the staple h by simply pressing 70 outward upon the inner surface of the bent portion of the hasps $g g$ with the hand the hasps will slip off the staple h together, and by continuing to exert a slight pressure in the same direction upon said hasps the crank-shafts C will be rocked so as to withdraw the 75 bolts—the entire series at one and the same operation—from the flap or locking-staples $a a$, when the latter can be quickly withdrawn and the flap thrown forward, thus permitting 80 of the ready and expeditious opening of the bag or pouch.

It is apparent that the closing and locking of the bag or pouch can be effected with equal facility and expedition, it only being necessary 85 to return the staples $a a$ after the proper disposition or lowering of the flap to its closed position through the required or opposite openings in the bag or pouch and through the openings in the shields c , the hasps $g g$ 90 then being moved or carried upward, so as to receive through their coincident openings the staple h , the bolts thereby being caused to engage their receiving-staples. The padlock is then adjusted upon the hasp-staple and its 95 shackle locked.

I am aware that rocking crank-shafts carrying bolts have before been employed on similar devices; but it has been the practice to use a single continuous shaft connected to a single 100 hasp, whereas I employ two independent shafts carrying hasps at their adjacent ends,

which hasps lie one on the other and simultaneously engage the staple. The advantage of this arrangement is that all cramping of the crank-shaft and bolts is avoided, and the 5 operation of locking and unlocking the bag is made easier. Further, it will be noted that the link-connections are swiveled on the upwardly-bent parallel pintles on the adjacent ends of the crank-shafts, whereby said link- 10 connections may be swung outward perpendicular to their normal positions before the crank-shafts are turned to withdraw the bolts.

Having thus described my invention, what I 15 claim as new, and desire to secure by Letters Patent, is—

1. In a mail bag or pouch lock, the combination of the independent crank-shafts carrying locking or drop bolts engaging staples on the cover-flap, the hasps connected to the 20 adjacent ends of said shafts arranged to fold one on the other and provided with coincident openings to engage a staple, and means to lock the hasps on the said staple, substantially as set forth.

25 2. In a mail bag or pouch lock, the combi-

nation of the independent crank-shafts carrying locking or drop bolts engaging suitable staples on the cover-flap, the hasps provided with angular link-connections F F, which are swiveled on upwardly-bent parallel pintles on 30 the adjacent ends of said shafts, said hasps being adapted to fold one on the other, and further provided with coincident openings to engage a staple, and means to lock the hasps on the staple, substantially as specified. 35

3. In a mail bag or pouch lock, the combination, with independent crank-shafts carrying locking-bolts to engage staples on the cover-flap, of the independent flat hasps G G, connected by swiveled links to the adjacent 40 ends of the said shafts and provided with coincident openings to engage a staple, and means to lock said hasps on the staple, substantially as specified.

In testimony whereof I affix my signature 45 in presence of two witnesses.

EDWIN F. DAVIS.
